UNITED STATES PATENT OFFICE

2,545,360

TRIP FOR AUTOMATIC PHONOGRAHS

Kurt T. Johnson, Chicago, Ill., assignor to J. P. Seeburg Corporation, Chicago, Ill., a corporation of Illinois

Application May 19, 1944, Serial No. 536,283

4 Claims. (Cl. 274--1)

1

This invention relates to trips for automatic phonographs adapted to initiate the record changing cycle thereof, and in some cases to terminate the operation of the phonograph. The trip of the present invention is adapted to be operated at the end of the reproduction of a record by the continued inward movement of the player arm which engages the record. In the case that the record is provided with an eccentric groove inside the recording groove, the trip is actuated by the reverse movement of the player arm. In the case that the record is provided with a spiral groove inside the recording groove the trip is actuated when the player arm is carried into a predetermined inner position. In many trips in wide use the amount of force necessary to actuate the trip is considerable and may cause considerable wear in the recording groove, particularly in the case of records having a long recording groove. If the needle pressure is reduced, the load presented by the trip can not be provided by the engagement of the needle with the tripping groove of the record.

One of the objects of the present invention is to provide a trip which can be operated with very little force, thus obviating any wear on the recording groove and permitting the trip to be affirmatively operated even with minute needle pressure.

A further object of the invention is to provide a trip which can be readily operated from a remote point so that the playing of an undesired recording or a record with a defective groove may be easily terminated.

The invention will readily be understood from the following description of a preferred embodiment thereof, taken in conjunction with the accompanying drawings, in which:

Fig. 1 is an elevational view showing the improved trip and associated elements of the phonograph;

Fig. 2 is a similar view showing the trip in tripped condition;

Fig. 3 is a plan view of the trip and associated phonograph elements;

Fig. 4 is an elevational view of the trip as viewed from the right in Figs. 1, 2 and 3, and

Fig. 5 is a perspective view showing the clutch elements controlled by the trip.

The present invention is illustrated as applied to the selective automatic phonograph described and claimed in Patent No. 2,287,139, issued April 1, 1941, to Carl G. Freborg. It is to be understood however that the improved trip is applicable to other automatic phonographs.

2

In this phonograph, a motor (not shown) drives a shaft 10 from which the turntable is driven. When the trip is actuated a cam shaft 11 is driven through one revolution to effect the various movements necessary for the changing of a record. The shaft 11 carries a worm gear 12 which meshes with a worm 13 carried by a shaft 14 in alignment with the shaft 10. The shaft 14 and the shaft 10 carry pins 15. During the playing of a record the pins 15 are out of engagement. The shaft 14, being held to the left as viewed in Fig. 5 by two prongs 16 which engage a collar at the end of the shaft 14 remote from the pins 15. The clutch is held disengaged by a pivoted latch 17 which engages an arm 18 rigidly carried by the shaft 19 which also carries the prongs 16. A spring 20 which engages the outer end of the shaft 14 biases the shaft 14 towards the shaft 10. It will readily be apparent from Fig. 5 that when the latch 17 is moved upwardly the spring 20 moves the clutch elements into engagement so that the motor drives the cam shaft 11 through one revolution. Near the end of the complete revolution a pawl 21 pivotally mounted on one of cams 22 on the cam shaft 11 engages an arm 23 rigidly carried by the shaft 19. The pawl 21 swings in clockwise direction against the tension of its spring 24, bringing an adjustable screw 25 carried by the pawl 21 into engagement with the arm 23. The arm 23 is thus moved in counter-clockwise direction and the pawl 21 snaps past the upper end of the arm 23 into its position in Fig. 1. The latch 17 drops and engages the arm 18 so that the clutch elements 15 are maintained in separated relation and the cam shaft 11 is no longer driven.

In the phonograph in the patent referred to, cams on the shaft 11 effect, during its rotation, the downward movement of the turntable to return the played record to its slide, the return of the slide to its position in the stack, the movement of the slide carrying the next record to be played out into alignment with the turntable, the return of the player arm to initial playing position and the upward movement of the turntable to bring the new record into cooperative relation with the player arm.

The player arm 26 is pivotally mounted on the upper end of a vertical shaft 27. The shaft 27 carries a radially directed roller 28. A cam 29 on the cam shaft 11 is adapted to engage the roller 28 after the turntable has moved the record out of engagement with the needle, so as to move the player arm back to its initial playing position. When the cam shaft 11 stops the roller 28

is located opposite a recess 30 in the cam 29 so that the player arm is freed to move inwardly as the next record is being played.

The present invention is primarily concerned with the trip whereby the movements of the player arm 26 control the unlatching of the latch 17 to effect engagement of the clutch elements 15. The shaft 27 carries a radial arm 31 upon which is pivotally mounted a pawl 32. The pawl 32 is freely pivoted so that one of its edges 33 projects upwardly and is normally located to the right of its pivot as shown in the dot and dash position in Fig. 4. During the playing of a record the arm 31 moves in the clockwise direction as viewed from above and the corner 33 of the pawl 32 is brought into engagement with the serrations 34 of a serrated member 34. The member 34 is rigidly mounted on the lower end of a latch 35 which is pivotally mounted at 36 on the flange 37 of a plate 38 which is rigidly mounted on the chassis. When the pawl 32 engages the serrated member 34 and the player arm 26 is moved back in counter-clockwise direction the pawl 32 carries the latch member 35 into its dot and dash position in Fig. 4 owing to the oblique relation between the corner 33 of the dog and its pivot.

The arm 31 carries an upwardly extending pin 39 which is adapted to engage a projection 40 extending outwardly from the latch 35, so that the latch 35 may be swung into its dot and dash position of Fig. 4 by a sufficiently large inward movement of the player arm on the record. Consequently, the latch 35 is swung into its dot and dash position of Fig. 4 by an eccentric groove at the end of the recording groove or by a spiral groove which extends inwardly from the recording groove. The latch 35 is biased towards latching position by means of a light weight 41 carried by an arm 42 on the latch 35. A lug 43 on the latch 35 adapted to engage the flange 37 limits the movement of the latch 35 in the clockwise direction.

The latch 35 is provided with a detent 44 which is adapted to engage the reduced end of a lever 45. The lever 45 is pivotally mounted at 46 on the plate 38 and its reduced end extends through an opening in the flange 37. At its other end the lever 45 carries an insulating contact 47 which normally engages a switch pole 48. The lever 45 is biased in the counterclockwise direction by a spring 49. A flexible switch pole 50 is located below the switch pole 48 and is biased downwardly away from the pole 48 and towards a switch pole 51. Normally the switch pole 50 is held in the position shown in Fig. 1 by means of a pin 52 carried by the shaft 19. When the latch 17 is elevated the pin 52 moves into its position in Fig. 2 and the pole 50 moves downwardly so as to make contact with the pole 51. In normal condition as shown in Fig. 1 the three poles 48, 50 and 51 are separated. The pole 50 is grounded. The pole 48 is connected to one terminal of an electromagnet 53 which is mounted above the latch 17. When the selector magnet is energized the latch 17 is moved upwardly and the clutch elements engage. The other terminal of the electromagnet 53 is connected to a source of power, shown by way of example as a battery 54. The other side of the source is grounded.

The poles 50 and 51 constitute a muting switch. For this purpose the pole 51 may be connected to the ungrounded side of the pickup or to another suitable point in the sound system. The pole 48 is connected to one side of a reject switch 55, the other side of which is grounded. The

switch 55 may be mounted on the phonograph or at any suitable position in remote relation to the phonograph.

The lever 45 carries an upwardly directed arm 56 which is adapted to be engaged by a projection 57 on the cam shaft 11 after it has moved through approximately 90°. The lever 45 is swung in the clockwise direction as viewed in Fig. 1 so that it is again latched down by the latch 35.

The operation is as follows:

At the end of the playing of a record the latch 35 is moved from its full line position into its dot and dash position in Fig. 4 in the manner previously described. This movement of the latch 35 removes the detent 44 from the end of the lever 45 so that the spring 49 is free to move the lever 45 in the counterclockwise direction as viewed in Fig. 1. The pole 48 is moved downwardly so that it engages the pole 51, thus completing the circuit of the electromagnet 53. The electromagnet attracts the latch 17 so that it disengages the arm 18. The spring 20 causes the clutch elements 15 to engage and rotate the shaft 19 partially in the clockwise direction as viewed in Fig. 1. The pin 52 is thus moved into its position in Fig. 2, permitting the pole 50 to move downwardly out of engagement with the pole 48 and into engagement with the pole 51, muting the sound system. This condition is shown in Fig. 2. After the cam shaft 11 starts to rotate the turntable moves downwardly and the cam 29 engages the roller 28, swinging the player arm back to initial playing position. During this return movement the pawl 32 slides past the serrated member 34. Thereafter the projection 57 engages the arm 56 and swings the lever 45 in the clockwise direction as viewed in Fig. 1 so that the latch 35 again latches it in its normal position. The switch pole 48 moves upwardly into its normal position. At the end of a complete revolution of the cam shaft 11 the pawl 21 swings the shaft 19 back to its initial position, terminating the drive of the cam shaft 11 and moving the switch pole 51 upwardly into its normal position and opening the muting circuit. The latch 17 again engages the arm 18, locking the shaft 19 in its normal position. If the switch 55 is closed during the playing of a record the electromagnet 53 is energized so that the operation just described is executed.

Although the invention has been described in connection with the specific details of a preferred embodiment thereof, it must be understood that such details are not intended to be limitative of the invention except in so far as set forth in the accompanying claims.

I claim:

1. In an automatic phonograph comprising a record changing mechanism, a trip mechanism comprising a member movable with the player arm in its translational movement over the record, a latch adapted to be released by said member at the end of the playing of a record, a member normally latched by said latch, a switch adapted to be closed by last said member when unlatched, a second latch normally maintaining said record changing mechanism inoperative, electromagnetic means arranged to be energized by said switch when closed for releasing said second latch to render said record changing mechanism operative, means controlled by said second latch for opening said switch when said second latch is unlatched, and means actuated by said record changing mechanism for return-

ing the first said normally latched member to latched condition and thereafter returning the switch to normal open condition.

2. In an automatic phonograph comprising a record changing mechanism, a trip mechanism comprising a member movable with the player arm in its translational movement over the record, a latch adapted to be released by said member at the end of the playing of a record, a member normally latched by said latch, a two pole 10 switch, one of said poles being arranged to be engaged by last said member when unlatched to close said switch, a second latch normally maintaining said record changing mechanism inoperative, electromagnetic means arranged to be energized by said switch when closed for releasing said second latch to render said record changing mechanism operative, means controlled by said second latch for causing the other pole of the switch to move away from the first mentioned pole to open the switch upon the unlatching of said second latch and means actuated by said record changing mechanism for returning the first said normally latched member to latched condition to effect return of the first said pole to normal position and thereafter returning the other pole to its normal position.

3. A trip for automatic phonographs having a clutch adapted to be engaged by said trip and a cam shaft adapted to be driven a complete revolution to effect record changing, comprising a member movable with the player arm in its translational movements, a latch adapted to be unlatched by said member at the end of the reproduction of a recording, a member normally latched by said latch, a normally open two pole switch, means biasing said normally latched member towards one of the poles of said switch whereby the switch is closed when said member is unlatched, a second latch, a clutch controlling member normally held by last said latch with the clutch disengaged, electromagnetic means adapted to be energized when the switch is closed to release second said latch and effect engagement of the clutch when the switch is 45

closed, and means controlled by said clutch controlling member for controlling the movement of the other switch pole to switch opening position, means on said cam shaft for returning first said normally latched member to latched condition and returning first said switch pole to normal position, and other means on said shaft for thereafter disengaging said clutch and returning second said switch pole to normal condition.

4. An automatic phonograph comprising a cam shaft for changing records, a continuously driven member, a clutch for connecting said shaft operatively to said driven member, a latch for retaining said clutch in disengaged condition, electromagnetic means adapted when energized to release said latch, a normally open switch controlling said electromagnetic means, an arm movable with the player arm in its translational movements, a second latch adapted to be released by said arm at the end of the reproduction of a recording, a member normally engaged by last said latch and biased towards said switch to close the switch when last said latch is released by said arm, means controlled by first said latch for opening said switch immediately after the electromagnetic means is energized, and means on said cam shaft for relatching the switch closing member and for thereafter returning the switch opening means to their initial conditions.
